ELECTRIC BRUSH STERILIZER

Charles M. Ellis, 812 Natches, Liberty, Mo. 64068

Filed Mar. 2, 1970, Ser. No. 21,706

Term of patent 14 years

Int. Cl. D24—99

U.S. Cl. D83—1

Fig. 1.

Fig. 2.

Fig. 3.

Fig. 4.

Fig. 5.

FIG. 1 is an enlarged elevational view of an electric brush sterilizer showing my new design;

FIG. 2 is a top plan view of my electric brush sterilizer with the lid on;

FIG. 3 is a top plan view of my electric brush sterilizer with the removable lid off;

FIG. 4 is a bottom plan view of my electric brush sterilizer; and

FIG. 5 is a sectional view taken generally along the line 5—5 of FIG. 1 in the direction of the arrows.

I claim:

The ornamental design for an electric brush sterilizer, as shown and described.
